UNITED STATES PATENT OFFICE.

FRANK W. STEERE, OF DETROIT, MICHIGAN.

FURNACE.

1,257,649.

Specification of Letters Patent. Patented Feb. 26, 1918.

Application filed July 31, 1915. Serial No. 42,889.

To all whom it may concern:

Be it known that I, FRANK W. STEERE, a citizen of the United States of America, residing at Detroit, in the county of Wayne and State of Michigan, have invented certain new and useful Improvements in Furnaces, of which the following is a specification, reference being had therein to the accompanying drawings.

10 It is a desideratum in an annealing or other furnace for bringing to a high heat or for heat treating metals, irrespective of the kind of work or industry in connection with which it is used, that it possess the following characteristics:—

15 Accurate control of temperatures; uniform temperature over the furnace hearth; uniform conditions for all stock being treated on the hearth irrespective of the variety 20 of shapes, sizes or materials; the preventing of the hot products of combustion from contacting the metal during its treatment; continuity of treatment of stock during the 25 operation of the furnace; fuel economy and maximum thermal efficiency; minimum loss by a cessation in operation; absolute freedom 30 from danger of explosion; simplicity of operation with protection to the operator; and adaptability to various processes involved in the production of a great variety of products.

An annealing furnace in accordance with this invention not only meets the above requirements but possesses many other advantages, all as hereinafter more fully set forth and as will more clearly appear after consideration of a preferred embodiment of my invention, which is illustrated in the accompanying drawing, wherein—

40 Figure 1 is an enlarged transverse vertical section through a furnace embodying the invention;

Fig. 2 is a horizontal sectional view taken on or about the line II—II of Fig. 1, showing diagrammatically, a double reversing or four-way valve, and

Fig. 3 is a longitudinal sectional view of the furnace, on the line III—III of Fig. 2.

In describing my invention by aid of the views above referred to, I desire to point out that the same are merely intended as illustrative of a furnace which is now in use, and I do not care to confine my invention to the precise construction and arrangement of parts shown. The following description is

therefore to be construed as including substitute or equivalent constructions and arrangements of parts.

As now erected, the furnace is located upon an inclined foundation 1, having a well 60 2 at the forward end of the furnace and a pit 3 at the rear end thereof. The furnace, *per se*, comprises a metallic shell including a bottom plate 4, a front wall 5, and a rear wall 6, said shell constituting a suitable 65 binding or reinforcement for a refractory structure 7.

In the foundation 1 are longitudinal channels 8, 9, 10 and 11 communicating with vertical chambers 13, 14, 15 and 16 through 70 openings 12 in the bottom plate 4, and in said chambers contiguous to said bottom plate, are foraminous supports 17 for ceramic material 18. This material is preferably crushed and sized and the chambers 75 filled with these spawls or the chambers may be filled with specially manufactured thin pieces of ceramic material of any desired shape to provide suitable regenerating chambers, and these chambers communicate with 80 combustion chambers 19 and 20 which are separated by a central division wall 21 extending upward to and supporting a hearth 22 which, together with the side walls 23 and an arch 24 supported thereby and spanning 85 the hearth, forms a closed muffle or retort 28 having a receiving opening 25 at the forward end of the furnace structure and a discharge opening 26 at the rear end thereof. The arch is spaced from the top of the furnace structure to provide a passage 29 which 90 also spaces the side walls from the structure and connects the combustion chambers 19 and 20 into which the upper ends of the chambers 13, 14, 15 and 16 open. The 95 flames and hot products of combustion are thus permitted to sweep over and around the muffle, heating it to a high temperature without coming into contact with the material being treated therein, and air and gas 100 to maintain combustion in one combustion chamber may be admitted thereto through the regenerating chambers which open into its bottom, and the products of combustion from that chamber, after passing around the 105 muffle into the other combustion chamber, may pass out through the two regenerating chambers opening into the bottom thereof.

To assist the feeding or travel of stock through the muffle from its inlet or receiv- 110

ing end 25 which may be closed by a suitable door or gate 30, to its discharge end 26 which may be closed by a like door, the muffle is constructed at an inclination in the 5 direction of its length, so that the stock placed upon the upper end of the hearth may be easily pushed along the parallel tracks or rails 27 laid thereon and discharged from the lower end without the 10 necessity for providing means within the muffle for moving the stock or articles along the hearth, the stock being discharged at the lower end by forcing it in at the upper end, thus providing a continuous operation. 15 Between the chambers 13, 14, 15 and 16 are passages 31 of less depth than the regenerating chambers and having the forward ends thereof in communication with the atmosphere through openings 32 in the 20 front wall 5 of the furnace. The rear or lower ends of these air passages 31 open into a transverse passage 33 having an outlet pipe 34. The walls of the passages are lined with metallic plates 35 and the roof 25 of each passage is supported in such a manner as not to interfere with the free passage of air from the forward end of the furnace to the rear end thereof through these passages. The linings for the air passages 30 constitute metallic jackets for the regenerating chambers 13, 14, 15 and 16, thus precluding any leakage from one chamber to another which would result in heat loss and less efficiency in operation. The metallic walls of 35 the air passages are cooled by the passage of air through the chambers, thus preventing the breaking down of the metallic plates forming the air tight jacket for the walls.

The pipe 34 is in communication with a 40 double reversing valve 38 located within the pit 3 and constructed upon the principle of an ordinary four-way cock. This valve has been diagrammatically illustrated in Fig. 2 as having connected thereto a gas supply 45 pipe 39, gas outlet pipes 40, 41, 42 and 43 communicating with the lower ends of the channels 8, 9, 10 and 11 respectively, and an exhaust pipe 44 for products of combustion. This exhaust pipe extends upwardly through 50 the bottom 45 of and discharges into a closed tower 46 which is in communication with the discharge opening 26 of the muffle or retort. In the tower 46 is a conventional form of endless conveyer 47 adapted to receive 55 the articles or stock from the muffle and carry the same upward in the tower where they are cooled during their travel, in the comparatively cool products of combustion discharged from the furnace, thus tending 60 to prevent oxidization.

As shown in Fig. 2, the valve 38 is so adjusted that gas passing through the valve from the supply pipe 39 enters the channel 10 and passes upwardly through the regenerating chamber 15 into the combustion

chamber 19. In this chamber, the gas comes with a supply of air drawn through the passages 31, pipe 34, valve, the pipe 43, and channel 11 into the regenerating chamber 16. The admixture in the combustion chamber 19 is ignited and the flames and hot products of combustion sweep over and around the muffle or retort 28 and pass from the other combustion chamber downwardly through the regenerating chambers 70 13 and 14 where a large portion of their heat is absorbed by the spawls, and through the channels 8 and 9, pipes 40 and 41, through the valve, and are discharged in a comparatively cool state into the tower 80 through the exhaust pipe 44.

This action is continued for a predetermined period of, say thirty minutes and then the valve 38 is operated to reverse the flow, causing the gas to pass into the regenerating chamber 14 and the air into the regenerating chamber 13 from which they enter and mix in the combustion chamber 20 and are ignited by the heat, their products of combustion then sweeping under and over the muffle or retort 28, passing downwardly through the regenerating chambers 15 and 16 which have been cooled by the ingoing gas and air during the previous cycle of operation and giving off their heat 95 to the spawls therein, and then discharging through the channels 10 and 11, valve 38, and exhaust pipe 44 into the tower in a cooled state. In this operation, it is to be noted that the air and gas passing through 100 the regenerating chambers 13 and 14 are pre-heated by the absorbed heat held in the material contained in the chambers and that the products of combustion are cooled by passing through the regenerating chambers 105 15 and 16 containing material which was cooled by air and gas passed through the chambers during the previous cycle of operation. The heat of the products of combustion is thus stored for use in heating the ingoing air and gas and the products of combustion leave the furnace in a comparatively cool state, thus effecting a great saving in fuel and making the cooled exhaust available for cooling the stock after it leaves the 110 muffle, thus tending to prevent the oxidization which might otherwise take place if cooled in the open air.

In the present well known types of furnace the material is loaded onto the hearth 115 from a doorway at the front of the furnace, the door closed, the material brought up to heat, the stock withdrawn through the same doorway, and then the stock quenched or air cooled according to the process involved. 120 From the very nature of such furnace constructions, the heating process is intermittent, resulting in a large heat loss, expenditure of time, energy and the space required 125 for the operation.

On the other hand, where the stock is fed through the furnace, passing in at one end and out at the other with a continuing movement in one direction as in the present construction, the operation carried on by the furnace may form a step in a manufacturing process, the same as any other machine which may perform any other operation upon the stock. The inclination of the hearth is also an important feature in certain manufacturing plants where it is desirable to have an extended hearth to give the desired capacity or to increase the length of travel through the furnace and a corresponding increase in the length of time which the stock will be subjected to the heat. The action of gravity is thus employed to assist in feeding the stock through the muffle, obviating the necessity for mechanical feeding means within the muffle to move the stock along the hearth.

The advantage to be gained by the use of a muffle having a stock receiving opening at one end and a discharge opening at the opposite end, is that the stock may be fed in at one end and taken out at the other with a continuing movement of the stock through the muffle and it is possible to control with accuracy the treatment temperature of the stock. If it is desired to maintain a temperature of seventeen hundred and fifty degrees Fahrenheit in the retort and a certain tonnage is to be hourly delivered from the furnace, the temperature is maintained, after the gas and air have been adjusted, by varying the rate of passage of the stock through the furnace. If the temperature tends to drop, the feeding of stock is slowed up. If the temperature tends to rise, the feeding of stock is speeded up. It has been found by a test extending over several weeks, that by a combination of these two methods of controlling the temperature, the temperature of the material on the furnace hearth is maintained within a variation of ten degrees, and this has been accomplished with ordinary labor and without the use of mechanical feed within the muffle, which feeding means may be dispensed with as the action of gravity is utilized to assist in the movement of the stock along the hearth which is inclined for the purpose.

Uniform conditions for all stock on the hearth at any one time is also important and this condition is attained by passing the stock with a continuing movement over the entire length of the hearth; that is, one piece after another is fed into the furnace at one end so that the stock is not piled up but is at the same depth on all parts of the hearth and passes out of the opposite end in the same manner, whereby all stock is subjected to the same heat conditions.

It is generally agreed by metallurgists that the closed muffle is the ideal furnace for heat treating operations for the reason

that such a furnace prevents the hot products of combustion from coming into contact with the metal. If the products of combustion carry an excess of oxygen, scaling results from such contact and it is also claimed that the steel tends to absorb impurities. The principal point urged against the muffle furnace so far, has been the high cost of fuel. This objection, however, has been eliminated in my furnace by using the regenerating chambers 13, 14, 15 and 16, which absorb and hold the heat that ordinarily passes out with the products of combustion, until taken up, upon reversal of flow, by the ingoing air and gas and returned to the muffle, as set forth in the operation of the furnace.

A cheap method of burning coal is to first convert it into producer gas, and this gas is the cheapest known fuel which is suitable to furnace work. It has the advantage of being very dilute and large volumes become necessary to produce the required heat. The products of combustion are therefore large in volume as compared with oil or a higher calorific power fuel, which makes local heating impossible. This difficulty from local heating is very serious in oil fired furnaces as it is very disastrous to brick work and necessitates frequent repairs. By my process of heat treating, the life of the brick work or body of the furnace is indefinitely prolonged.

It is sometimes urged that gas furnaces are dangerous because of inexperienced operators attempting to light them. This feature has been eliminated in connection with my furnace from the fact that after the furnace is once placed in operation, there is no occasion to relight it, unless shut down for a considerable period of time, as the regenerating chambers and the body of the furnace hold sufficient heat to ignite the combustible fuel when it is turned on.

By the method of burning gas involved in my furnace the products of combustion leave the furnace at a very low temperature and they are therefore available for cooling the stock as it leaves the hearth. The tower 46 simply constitutes a receptacle into which the stock is delivered and cooled by the cool products of combustion before being discharged into the atmosphere. It is well known that oxidizing and scaling result from cooling stock in the open air, and I have found that this difficulty is largely eliminated by subjecting the stock to the cooling action of the products of combustion which have had their initial heat removed and returned to the furnace hearth by the regenerating chambers.

Considering the regenerators, I obtain a distinct advantage by eliminating the ordinary brick checkered work built up of the shapes usually known as "soaps," and substituting therefor a very thin material

which is capable of absorbing and giving off heat very rapidly. In my furnace, the ceramic material may be in very thin sections disposed so that at no one place will there be a great thickness of material which heat must penetrate. The material may be crushed and sized, and the regenerating chambers filled with this inexpensive material. The exact nature of the ceramic material and its disposition depends upon the use to which the annealing furnace is put. In the test above referred to, I have found that after the gas and air is closed off for a period of thirty-eight hours, the drop in temperature is so small that the furnace can again be placed in operation after a few minutes' heating. This is due largely to the construction of the furnace whereby a thorough heat insulation is secured. It is therefore apparent that there is practically no "stand by" loss as long as the furnace is used each day, and that it is only necessary to manually ignite the combustible fuel when the furnace is first put in operation.

25 By placing the regenerating chamber directly under the hearth, uniformity of temperature throughout its area is secured, and minimum loss of heat by a radiation through the furnace walls is secured, and the absorbed heat of the regenerators is imparted to the hearth. Like pyrometer readings have been obtained at various points along the hearth, and this accurate control of the temperature has been obtained by regulating the quantity of air and gas admitted to the furnace by the valve, and also by regulating the feeding of stock into the furnace, as heretofore set forth.

The construction and arrangement of regenerating chambers in a furnace will be found to be applicable to furnaces for making gray iron castings, furnaces for use in the glass industry, and in fact to most all furnaces where fuel economy and speed of operation are desired, and while in the drawings is shown a furnace especially adapted for annealing purposes, the same construction, with slight modifications, is applicable to forge work, drop forging operations, and almost an indefinite number of other heating and heat treating operations used in modern industries.

What I claim is:—

1. A muffle having a stock receiving opening at one end thereof and a discharge opening at its opposite end, a receptacle in communication with the discharge opening of said muffle adapted to receive stock therefrom, and means for heating said muffle by products of combustion and for discharging the products of combustion into said receptacle after having given off their heat to the muffle to prevent oxidization of stock received therein from the muffle.

2. A muffle having a stock receiving

opening and a discharge opening, a receptacle in communication with the discharge opening of said muffle to receive stock therefrom, means for directing products of combustion to said muffle to heat the same and for conducting said products of combustion to said receptacle, and means in the path of flow of the products of combustion for removing heat from said products of combustion after the same have passed and heated said muffle and before they enter said receptacle.

3. In a furnace, the combination of a muffle, a combustion chamber adjacent said muffle, regenerating chambers in communication with said combustion chamber to supply fuel thereto and conduct products of combustion therefrom, means for reversing the flow of fuel and products of combustion through said regenerating chambers, means between said regenerating chambers adapted to supply air thereto to mix with the fuel and form a combustible mixture, and a receptacle to receive products of combustion from said chambers and arranged to receive the discharge material from the muffle.

4. In a furnace, a muffle, connected combustion chambers adjacent said muffle, a pair of regenerating chambers in communication with each combustion chamber, means for alternately supplying air and fuel to each pair of chambers to reverse the flow, each pair being adapted to alternately receive and conduct away the products of combustion from the combustion chamber with which it is in direct communication, and means for receiving the cooled products of combustion from said chambers and arranged to receive material from the muffle to be cooled by the cool products of combustion.

5. In a furnace, a muffle adapted to be heated by products of combustion and adapted to receive stock at one end thereof and discharge stock at the opposite end, sets of chambers adapted to be alternately used for supplying products of combustion and fuel, said chambers being disposed whereby each set is adapted for alternate use as an inlet for fuel and an exhaust for the products of combustion, and a receptacle to receive stock from the muffle connected with said chambers to receive the cooled products of combustion therefrom.

6. In a furnace, a muffle, a combustion chamber adjacent the muffle for heating the same, regenerating chambers in communication with said combustion chambers to supply fuel and air thereto and to conduct products of combustion away from said combustion chamber, means for reversing the flow of fuel and air and products of combustion through said regeneration chambers, air passages adjacent said regenerating chambers in communication therewith and controlled by said reversing means, and a

receptacle to receive stock from the muffle and the exhaust products of combustion from the said regenerating chambers.

7. In a furnace, a muffle adapted to receive stock at one end thereof and discharge stock at the opposite end, a combustion chamber adjacent said muffle, sets of regenerating chambers adapted to be alternately used for supplying fuel to said combustion chamber and exhausting products of combustion therefrom, air passages between said regenerating chambers, a tower adapted to communicate with said regenerating chambers

to receive exhaust products of combustion therefrom and adapted to receive stock from 15 said muffle, and a valve common to all of said chambers and passages for controlling the direction of flow of fuel and products of combustion therethrough.

In testimony whereof I affix my signature 20 in presence of two witnesses.

FRANK W. STEERE.
